A. D. HEYL

PLATFORM ELEVATOR

Filed Jan. 27, 1922

UNITED STATES PATENT OFFICE.

ALBERT D. HEYL, OF NEW YORK, N. Y.

PLATFORM ELEVATOR.

Application filed January 27, 1922. Serial No. 532,121.

To all whom it may concern:

Be it known that I, ALBERT D. HEYL, a citizen of the United States, residing in the city and county of New York, State of New York, have invented a new and useful Platform Elevator, of which the following is a specification.

My present invention comprehends a novel construction of a platform elevator of the type which does not carry an operator and wherein novel mechanism is employed for controlling its operation.

It further comprehends a novel construction and arrangement of manually controlled devices for the mechanism employed to effect the raising and lowering of the platform.

Other novel features of construction and advantage will hereinafter more clearly appear in the detailed description of my invention.

For the purpose of illustrating my invention, I have shown in the accompanying drawings a form thereof which is at present preferred by me, since it will give in practice satisfactory and reliable results. It is to be understood, however, that the various instrumentalities of which my invention consists can be variously arranged and organized and that my invention is not limited to the precise arrangement and organization of these instrumentalities as herein shown and described.

Figure 1 represents a platform elevator embodying my invention.

Figure 2 represents in elevation a portion of the construction seen in Figure 1.

Similar numerals of reference indicate corresponding parts.

1 designates stationary guides of any desired character, with which cooperate the platform or gig 2. The gig 2 has connected to it a hoisting cable 3 which passes over a sheave 4 and around a drum 5 to which its free end is connected in any desired manner. The drum 5 is mounted on a shaft 6 having eccentric bearings 7, supported in any desired or conventional manner. The shaft 6 has fixed to it a friction wheel 8, which, at desired times, cooperates with a stationary brake shoe 9 carried by the stationary support 10. The drum shaft 6 is arranged between the pinion shaft 11 and the brake

shoe 9, so that the friction wheel 8 is free to rotate and by adjustment of the eccentric bearings can be brought into contact with the friction pinion 12 on the shaft 11 or into contact with the brake shoe 9.

13 designates a motor of any desired type which is intergeared by means of gear wheels 14 and 15 respectively with the shaft 11.

The eccentric bearings 7 have connected to them an arm 16 provided with an adjustable counterbalance 17, and connected to this arm is one end of a cable 18 which passes over the sheaves 19 and is connected at its other end to a latch bar 20, guided in a guide bracket 21, supported in such manner that it is stationary.

The lower end of the latch bar 20 has connected to it at one end the cable 21', which passes around the adjustably mounted sheave 22 and then around a sheave 23, and the free end of such cable 21' is connected to a weight 24, which is in the path of the platform or gig 2 during its upward movement. The platform 2 is provided with a head 25 to contact with the weight 24 during the operation.

The sheave 22 is mounted in a block 26 and to this block is connected the ends of the cable 27, and, as is best understood from Figure 2, this cable passes around sheaves 28 mounted in stationary brackets 29.

The latch bar 20 is provided with a series of apertures 30, in order that a latch block 31 can be adjustably secured to the latch bar 20.

32 designates a latch which is in the form of a lever pivoted at 33 to the bracket 21, and a spring 34 is provided one end of which is fixed to the bracket 21 and the other end of which bears against the latch 32 to effect its movement into latching position.

The latch 32 has connected to it a cable 38 having a grasping handle 35 by means of which it may be actuated, as will be hereinafter explained.

36 designates a cable having an actuating handle 37 at one end and having its opposite end passing around the sheave 19 and connected to the arm 16 so that when this cable is drawn downwardly the arm 16 will be raised, thereby causing friction wheel 8 to move out of contact with the brake shoe

9 and the platform or gig 2 will be permitted to move downwardly by gravity.

The winding drum 5 and the friction wheel 8 rotate in unison, and by adjustment 5 of the arm 16 to vary the eccentricity of the bearings 7, the friction wheel 8 will be power driven, or its rotation arrested by the brake shoe.

When the friction wheel 8 is floating between its pinion 12 and the brake shoe 9, the weight 24 is greater than the weight of the counterbalance 17, so that when the latch 32 is tripped by a pull on the cable 38, the weight 24 drops and causes the cable 21 to raise the arm 16, thereby adjusting the eccentric bearings to cause the friction wheel 8 to engage the motor driven friction pinion 12. The friction wheel 8 is thus rotated, and the hoisting cable wound up on the hoisting drum 5 to cause the upward travel of the platform or gig 2.

Sheave 28 is operated by a handle 39 and has recesses 40 to receive a pin 41 carried by the sheave bearing.

25 This upward movement continues until the platform or gig 2 meets and raises the weight 24. As the weight 24 is raised, the weight 17 moves downwardly, thus turning the eccentric bearings and causing the friction wheel 8 to move out of engagement with its driving pinion 12 and into engagement with the brake shoe 9, whereupon the gig 2 will be brought to rest, as is apparent.

The upward travel of the platform can 35 be arrested at any point by adjusting the position of the sheave 22 by means of the cable 27, as is apparent.

It will be apparent that in accordance 40 with my invention, I provide means which automatically operate to stop the upward travel of the platform or gig at any desired height and thus prevent any overrunning or damage to the machinery, since the power is automatically cut off by the raising of 45 the weight 24 by the platform or gig when it approaches the limit of its upward travel. When the latch bar 20 moves up, due to this action, it will be apparent that the latch block 31 will pass by the latch 32, so that 50 the cam face of the latter can slide beneath the latch block 31 due to the action of the spring upon the latch, so that the platform will be retained in the position at which it has been arrested.

55 It will now be apparent that I have devised a novel and useful platform elevator, which embodies the features of advantages enumerated as desirable in the statement of the invention and the above description, and 60 while I have in the present instance, shown and described a preferred embodiment thereof which will give in practice satisfactory and reliable results, it is to be understood that such embodiment is susceptible of modification in various particulars with

out departing from the spirit or scope of the invention or sacrificing any of its advantages.

Having thus described my invention, what I claim as new and desire to secure by Letters Patent, is:—

1. In a platform elevator, the combination with a friction drive and a brake shoe, of a friction wheel having eccentric bearings and interposed between said friction drive and brake shoe, a counterbalanced arm connected with said bearings to cause the friction wheel to co-operate with its friction drive or said brake shoe or to float free between them, a hoisting drum operatively connected with said friction wheel to move in unison with it, a gig, a cable connected with said hoisting drum and with said gig, a weight in the path of the upward travel of said gig of greater weight than said counterbalance, latch mechanism operatively connected with said weight and with said arm and automatically set by said weight when the latter is moved upwardly by said gig to retain said friction wheel in contact with said brake shoe, manually controlled means to release said latch mechanism to cause said weight to move said arm and thereby cause the friction drive to drive said friction wheel, and manually controlled means to actuate said counterbalanced arm to effect the raising of said gig.

2. In a platform elevator, the combination with a friction drive and a brake shoe, of a friction wheel having eccentric bearings and interposed between said friction drive and brake shoe, a counterbalanced arm connected with said bearings to cause the friction wheel to co-operate with its friction drive or said brake shoe or to float free between them, a hoisting drum operatively connected with said friction wheel to move in unison with it, a gig, a cable connected with said hoisting drum and with said gig, a weight in the path of the upward travel of said gig of greater weight than said counterbalance, latch mechanism operatively connected with said weight and with said arm to retain said friction wheel in contact with said brake shoe, manually controlled means to release said latch mechanism to cause said weight to move said arm and thereby cause the friction drive to drive said friction wheel, and independent manually controlled means to cause said friction wheel to engage its friction drive.

3. In a platform elevator, the combination with a friction drive and a brake shoe, of a friction wheel having eccentric bearings and interposed between said friction drive and brake shoe, a counterbalance arm connected with said bearings to cause the friction wheel to co-operate with its friction drive or said brake shoe or to float free between them, a hoisting drum operatively connected with

said friction wheel to move in unison with it, a gig, a cable connected with said hoisting drum and with said gig, a weight in the path of the upward travel of said gig of greater weight than said counterbalance, latch mechanism operatively connected with said arm to retain said friction wheel in contact with said brake shoe, a pair of spaced sheaves, a cable passing around said sheaves, a block to which the ends of said cable are connected, a cable connected to said weight passing through said block and connected to said latch mechanism, means to release said latch mechanism to cause said weight to move said arm and thereby cause the friction drive to drive said friction wheel, and said weight when raised by said gig effecting the relatching of said latch mechanism and causing said friction wheel to engage its brake shoe.

4. In a platform elevator, the combination with a friction drive and a brake shoe, of a friction wheel having eccentric bearings and interposed between said friction drive and brake shoe, a counterbalanced arm connected with said bearings to cause the friction wheel to co-operate with its friction drive or said brake shoe or to float free between them, a hoisting drum operatively connected with said friction wheel to move in unison with it, a gig, a cable connected with said hoisting drum and with said gig, a weight in the path of the upward travel of said gig of greater weight than said counterbalance, latch mechanism operatively connected with said weight and with said arm to retain said friction wheel in contact with said brake shoe, said latch mechanism including a stationary bracket, a latch bar slidable therein, a latch block adjustable on said bar, a latch in the form of a spring pressed lever to engage said latch block, and means to release said latch mechanism at the will of the operator, means to adjust the position of said weight, and means to

release said latch mechanism to cause said weight to move said arm and thereby cause the friction drive to drive said friction wheel.

5. In a platform elevator, a hoisting drum, a friction drive and a brake shoe, a friction wheel co-operating with said drive and brake shoe and connected with said drum, a counterbalanced arm to move said wheel into contact with said friction drive or said brake shoe, a gig, a cable connecting said drum and gig, a latch bar, a cable connecting said latch bar and arm, a latch block adjustable on said latch bar, a spring actuated latch to engage said latch block, a weight in the path of the upward movement of said gig, a cable connecting said weight and latch bar, and a manually actuated cable connected with said latch to effect its release.

6. In a platform elevator, a hoisting drum, a friction drive and a brake shoe, a friction wheel between said friction drive and brake shoe and connected with said drum, a counterbalanced arm to move said wheels into contact with said friction drive or said brake shoe, a gig, a cable connecting said drum and gig, a weight in the path of the upward travel of said gig of greater width than said counterbalance, latch mechanism connected with said arm and including a latch bar, a cable connecting said latch bar and said weight, a pair of spaced sheaves, a cable fastened around said sheaves, a pulley block to which the free ends of said sheave cable are connected, a third sheave around which the pulley passing to said weight passes, such cable also passing through the pulley of said pulley block, a handle connected with one of the sheaves around which the pulley block cable passes for adjusting the height of said weight, and means to lock the handle carrying sheave in a position to which it has been adjusted.

ALBERT D. HEYL.
